(57) CLAIM

The ornamental design for a push-button unit, as shown and described.

DESCRIPTION

The push-button unit claimed in the present application is for making electrical contacts, but could be used for triggering any type of device, so as to be more aesthetically pleasing.

FIG. 1 is a front elevational view of push-button unit embodying the new design thereof;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front, left perspective view thereof; and,

FIG. 8 is a bottom, rear, left perspective view thereof.
